UNITED STATES PATENT OFFICE

HENRY G. JOHNSON, OF EAST HAMPTON, CONNECTICUT, ASSIGNOR TO SUMMIT THREAD COMPANY, OF EAST HAMPTON, CONNECTICUT, A CORPORATION OF MAINE

SEWING-MACHINE SHUTTLE BOBBIN

Application filed December 4, 1928. Serial No. 323,757.

This invention relates to a bobbin for a sewing-machine shuttle, the bobbin being rotatable in the shuttle, and composed of a cylindrical cop tube, an annular thread mass wound thereon, and discoidal heads of sheet material, such as paper or sheet metal. The heads have central apertures receiving the ends of the tube, the heads being confined on the annular ends of the thread mass by upset portions of the tube ends.

The shuttle is usually provided with a spring or brake exerting sufficient frictional pressure on the bobbin to produce a suitable tension on the thread and prevent the bobbin from spinning or overrunning in the shuttle, as shown, for example, by the patent to Bates, No. 569,316, October 13, 1896.

The brake bears on one of the bobbin heads, and not only regulates the rotation of the bobbin, but also has a tendency to force the head sidewise toward the opposite head. The margins of the head orifices should be so firmly engaged with the periphery of the tube as to prevent sidewise movement of either head by pressure of the brake thereon. Heretofore the head orifices have been circular, and have not been adapted to grip the tube with sufficient force to prevent independent rotation of the tube in the heads, and inward sidewise movement of the head with which the spring or brake contacts, so that when thread is being drawn from the bobbin, the thread mass and tube are liable to be rotated independently of the brake-pressed head, the rotation of which is opposed by the brake. The independent rotation of the thread mass and tube causes the margin of the orifice in the brake-pressed head to wear the tube, so that the pressure of the brake on said head forces it toward the opposite head, and so increases the pressure of the brake-pressed head on the thread mass as to objectionably increase the tension of the thread being withdrawn, and cause breakage thereof.

The object of my invention is to obviate this objection.

Of the accompanying drawings forming a part of this specification,—

Figure 1 is an end view of a bobbin to which my invention relates.

Figure 2 is a side view of the same.

Figure 3 is an enlarged view of one of the heads of the bobbin.

Figure 4 is a section on line 4—4 of Figure 3.

Figure 5 is an enlarged section on line 5—5 of Figure 1.

Figure 6 is an enlarged end view of the bobbin, a portion being shown in section on the plane indicated by line 6—6 of Figure 5.

Figure 7 is an enlargement of a portion of Figure 3.

Figure 8 is an enlargement of a portion of Figure 6.

The same reference characters indicate the same parts in all of the figures.

The bobbin is composed of a cylindrical cop tube 12, an annular thread mass 13, universally wound thereon, and discoidal heads 14 of sheet material, preferably paper, each having a central orifice 15, the orifices of the heads receiving the ends of the tube 12. The heads are confined on the annular ends of the thread mass 13, in accordance with the usual practice, by upset portions of the tube ends as shown by Figure 5.

Heretofore the margins of the head orifices 15 have been circular and concentric with the peripheries of the heads, the tube ends closely fitting the margins of the head orifices, and bearing with a uniform pressure on all portions of said margins, so that the hereinafter described locking of the heads to the tube ends, to prevent independent rotation of the tube in the heads, is not effected.

In carrying out my invention I impart to the margin of each head orifice 15 a non-circular form, which is such that the margin includes a plurality of tube-gripping portions which are nearer the centers of the heads than other portions alternating with the gripping portions, the relative proportions of the tube and the head orifices being such that said gripping portions exert a sufficient gripping pressure on portions of the periphery of the tube, to lock the heads to the tube and prevent independent rotation of the tube in the heads.

6 The non-circular form is preferably provided by imparting the octagonal form shown by Figures 3 and 7 to the margin of the orifice, so that said margin includes a plurality of straight-edged gripping portions 16, and a plurality of reentrant portions 17, alternating with the gripping portions.

10 A line 18 (Figure 7) extending between two diametrically opposite reentrant portions 17, is longer than a line 19 extending between two diametrically opposite gripping portions 16. The length of the line 18 is substantially equal to the diameter of the tube 12. It will be seen, therefore, that when the 15 heads are forced on to the ends of the tube, the gripping portions 16 are compressed and caused to exert a greater gripping force on the tube than the reentrant portions 17, the margin of the head orifice being caused to conform to the periphery of the tube, as indicated by the full line circle 20 in Figures 20 6 and 8.

25 I have found that when the head orifices are formed as shown, and the relative diameters of the tube and the orifices are as above described, the gripping pressure of the margins of the head orifices on the periphery of the tube is sufficient to prevent independent rotation of the tube in the heads, 30 and obviate the objection heretofore stated.

35 I do not limit myself to the octagonal form of the margins of the head orifices, it being obvious that said margins may have other non-circular forms capable of accomplishing the described result.

I claim:

40 A shuttle bobbin composed of a cylindrical cop tube, an annular thread mass wound on said tube, and discoidal heads of sheet material having central orifices receiving the ends of the tube, the heads being held against the annular ends of the thread mass by upset portions of the tube ends, and the margins of said head orifices each including a plurality of tube-gripping portions which exert 45 greater pressure on the tube than other portions alternating with said gripping portions, the diametrical distance between the latter corresponding to the exterior diameter of the 50 tube, whereby said gripping portions will exert a sufficient gripping pressure on portions of the periphery of the tube to prevent rotation of the tube and thread mass relative to the heads.

55 In testimony whereof I have affixed my signature.

HENRY G. JOHNSON.
